UNITED STATES PATENT OFFICE

PERCY ROOTES, OF WINDSOR, ENGLAND, ASSIGNOR TO BRANDES LABORATORIES, INC.,
OF NEWARK, NEW JERSEY, A CORPORATION OF NEW JERSEY

ELECTROMAGNETIC SOUND REPRODUCER

Application filed June 11, 1928. Serial No. 115,210.

My invention relates broadly to electromagnetic sound reproducing systems and more particularly to a cabinet apparatus and mounting for broadcast receiving apparatus.

One of the objects of my invention is to provide a simplified mounting for an electromagnetic sound reproducer in association with signal receiving apparatus. Another object of my invention is to provide a unitary electromagnetic sound reproducer structure which may be mounted within a cabinet by a simplified method of inserting the electromagnetic sound reproducer within the front of a panel structure in such manner that the reproducer may be readily removed for inspection and repair from time to time.

Another object of my invention is to provide a removable electromagnetic sound reproducer structure which may be readily mounted in a cabinet in association with broadcast receiving apparatus and removed as a unitary structure from the cabinet without disturbing the delicate parts of the electromagnetic sound reproducer and interfering with the adjustment thereof.

A further object of my invention is to provide an electromagnetic sound reproducer in which a conical diaphragm is operated from an electromagnetic driver, a frame member being provided for the several parts of the electromagnetic sound reproducer, which frame member is readily insertable into and removable from the cabinet structure for inspection and repair of the several parts of the sound reproducer.

A still further object of my invention is to provide a frame structure for an electromagnetic sound reproducer which is readily mountable within an apertured panel associated with a radio receiving apparatus cabinet with a latch mechanism for maintaining the frame structure in position within the panel in such manner that the electromagnetic sound reproducer is readily removable for repair or adjustment from time to time.

My invention will be more clearly understood from the specification hereinafter following by referring to the accompanying drawings wherein:

Fig. 1 shows a plan view of the electromagnetic sound reproducer of my invention with parts partially in cross-section; Fig. 2 is a front view of the sound reproducer looking from the front of the panel structure; Fig. 3 is a side elevation of the electromagnetic sound reproducer with the diaphragm and frame structure partially broken away and shown in cross-section to illustrate more clearly the removable mounting of the sound reproducer within the panel; Fig. 4 is a rear view of the electromagnetic sound reproducer removably mounted in the panel structure; Fig. 5 is a side elevation showing more clearly the removable electromagnetic sound reproducer structure with relation to the panel of the receiving cabinet; Fig. 6 shows the frame of the electromagnetic sound reproducer slightly canted in position to be removed from the panel structure; and Fig. 7 is a view illustrating the several parts of the electromagnetic sound reproducer in the process of removal from the panel structure.

Heretofore in the mounting of an electromagnetic sound reproducer of the conical diaphragm type in a cabinet it has been the practice to mount the electromagnetic driver separately from the sound reproducing diaphragm. This arrangement requires tedious adjustment of the driving link, the apex of the conical diaphragm and the armature of the electromagnetic driver. Extreme care must be taken with respect to the spacial relation between the armature and the pole pieces of the electromagnetic driver. Where the driver and the diaphragm are mounted independently on separate supporting structures there is a tendency for many irregularities to exist in the arrangement of parts. Considerable difficulty has also been experienced in mounting the independent parts within a cabinet structure, for it has required the tedious adjustment between the driving link and the apex of the cone diaphragm and often there is very little space within a cabinet structure which also includes the radio receiving apparatus in which this adjustment may be performed. By my invention I provide a unitary frame structure carrying both the electromagnetic driver and the

frame support for a sound reproducing diaphragm. The structure is arranged for ready insertion into the panel of a radio receiving set cabinet with means for permitting the ready removal of the entire structure for inspection and repair.

Referring to the drawings in more detail reference character 1 designates generally a cabinet which may house broadcast receiving apparatus, where the apparatus is provided with a conical panel 2. A panel 3 is provided in the apparatus into which the electromagnetic sound reproducer may be inserted from the front thereof. The electromagnetic sound reproducer includes a conical diaphragm 4 supported at its periphery by a frame support 6 having a rim member 7 set therein. An ornamental grille structure 5 is provided which is insertable into the front of the panel structure 3 flush with the plane of the panel structure. A plurality of arms 9 extend from selected points around the frame structure 6 and provide a supporting seat 10 for an electromagnetic driver contained within housings 11 and 12.

Located around the periphery of the aperture 8 in the panel 3 I provide a plurality of abutment strips 14, 15, 16 and 17 having a contour similar to the contour of the aperture 8 against which the rear face of the supporting rim 6 may abut for securing a rigid mounting of the removable electromagnetic sound reproducer apparatus within the apertured panel. A lip member 18 is secured to the rear wall of the frame structure 6 enabling the sound reproducer to be readily seated within the apertured panel. Diametrically opposite the depending lip 18 I provide a latch member 19, the movement of which is governed and limited by means of a guide and stop 20 which forms an abutment with an extending lip on the latch 19. The latch 19 is normally spring pressed outwardly by means of spring 21 in such manner that the latch 19 tends to extend behind the rear wall of panel 3 in the same manner in which the depending lip 18 extends behind the rear wall of panel 3.

In order to provide for the ready removal of the electromagnetic sound reproducer apparatus from the panel structure a portion of the panel 3 is cut away at 22 at a slight angle. This permits the frame structure of the electromagnetic sound reproducer to be slightly canted for the removal thereof from the front of the panel, as represented more clearly in Figs. 9 and 10.

In order to cover the frame of the electromagnetic sound reproducer an ornamental grille 5 is provided having an outer periphery conforming with the contour of the aperture 8 of the panel 3 and this grille is readily removable to permit the ready removal of the electromagnetic sound reproducer. The grille is provided with socket members

26 at spaced intervals about its periphery and into these sockets ball members 23 pressed by spring 24 may be snapped. In removing the electromagnetic sound reproducer from the cabinet structure a thin edged tool is utilized to press back the ball members 23 for the quick removal of the grille 5. The tool is then passed around the angular wall 22 of aperture 8 for moving down the latch device 19 for permitting the ready removal of the electromagnetic sound reproducer from the cabinet structure.

In Fig. 4 I have shown the arrangement of the electromagnetic sound reproducer as removably mounted in panel 3. The construction of the removable loud speaker apparatus permits ready assembly of the sound reproducer within the radio receiving apparatus cabinet and introduces a considerable saving in the time required for assembling the apparatus at the same time that inspection and repair may be conveniently made at required intervals without disturbing the adjustment of the acoustical apparatus.

By latching the sound reproducer in position with respect to the sounding board or panel structure an acoustic coupling is provided between the conical shaped sound reproducing diaphragm and the sounding board. The complete electromagnetic sound reproducer is readily removed from the panel structure and the coupling reestablished when the sound reproducer is again latched into the sounding board. The acoustic coupling thus provided secures a cooperative effect between the conical shaped sound reproducing diaphragm and the panel or sounding board into which the sound reproducer is inserted or moved to a position where the conical shaped sound reproducing diaphragm has its peripheral edge in a position substantially within the plane of the sounding board.

While I have illustrated my invention in certain preferred embodiments I desire it to be understood that modifications may be made without departing from the spirit of my invention. For example, I have illustrated an elliptical cone diaphragm mounted on a horizontal axis within the radio receiving apparatus cabinet structure. It will be understood that other shapes of diaphragm may be employed or that the elliptical cone may be mounted on a vertical axis within a cabinet structure, the several parts of the frame being re-arranged to conform with the modified mounting. Other and further modifications may be made, and I intend no limitations upon the invention other than are imposed by the scope of the appended claims.

What I claim as new and desire to secure by Letters Patent of the United States is as follows:

1. A loud speaker reproducer comprising in combination an apertured panel structure, a frame member arranged to snugly fit within

5 said apertured panel structure, a conical shaped sound reproducing diaphragm, an electromagnetic driver carried by said frame member, and a plurality of abutments carried by said panel structure for engagement by said frame member for supporting said frame member in said panel structure for acoustically coupling said conical shaped sound reproducing diaphragm with said panel structure.

10 2. A sound reproducer including an apertured sounding board, a frame structure arranged to be removably and detachably mounted in said sounding board, said frame structure carrying a conical shaped sound reproducing diaphragm and an electromagnetic driver therefor, a flange member positioned on the peripheral edge of said frame structure for abutment with the rear of said sounding board, and a plurality of flanges positioned on said apertured sounding board for abutment with the peripheral edge of said frame structure.

15 3. A sound reproducer including an apertured sounding board, a frame structure arranged to be removably and detachably mounted in said sounding board, said frame structure carrying a conical shaped sound reproducing diaphragm and an electromagnetic driver therefor, a plurality of flange members secured to the rear of said apertured sounding board and projecting inwardly therefrom, and a separate flange member secured to the peripheral edge of said frame structure and located between a pair of said first mentioned flange members, said flange members operating to align said frame structure in the plane of said sounding board.

20 4. A sound reproducer including an apertured sounding board, a frame structure arranged to be removably and detachably mounted in said sounding board, said frame structure carrying a conical shaped sound reproducing diaphragm and an electromagnetic driver therefor, a plurality of flat strip members each having a contour conforming to the shape of said apertured sounding board for providing abutments for said frame structure, and a depending flange member and a latch mechanism carried by said frame structure at diametrically opposite points thereon for locking said frame structure within said apertured sounding board in abutment with said strip members.

25 55 In testimony whereof I affix my signature.
PERCY ROOTES.
